UNITED STATES PATENT OFFICE.

GARNET W. MCKEE, OF ROCKFORD, ILLINOIS.

METAL-MELTING FURNACE.

1,328,236.

Specification of Letters Patent. Patented Jan. 13, 1920.

Application filed November 12, 1917. Serial No. 201,541.

To all whom it may concern:

Be it known that I, GARNET W. MCKEE, a subject of the King of Great Britain, residing at Rockford, in the county of Winnebago and State of Illinois, have invented certain new and useful Improvements in Metal-Melting Furnaces, of which the following is a specification.

This invention relates to furnaces adapted for melting soft metals to be poured, and has more particular reference to the melting of linotype metal and the pouring thereof into molds to cast pigs suitable for use in melting pots of linotype machines.

The melting furnaces heretofore provided for this purpose are unsatisfactory in many respects, chiefly in that they are not as economical and efficient in their operation as is desired. Too much time and labor is required in the operation of melting and pouring; and in some instances wherein an effort has been made to expedite the pouring by the provision of a series of movable molds, facilities are lacking for quick continuous usage and safe operation.

I have, therefore, aimed primarily, to provide a melting furnace of generally improved construction by which soft metals may be melted and cast very efficiently, economically and safely.

In furtherance of this aim, my invention contemplates various objects, certain of which will now be briefly mentioned. One object is to provide for heating the melting pot in a most efficient manner and for properly housing the pot so as to convey away the gases resulting from the gas flames. Another object is to provide a construction by which the metal may be quickly and easily poured successively into a plurality of molds, the flow of metal being very accurately controlled by simple manipulation of a movable spigot and a valve controlling member. A further object is to provide a valve and spigot structure of simple and novel design which will enable the metal to be delivered from the pot to the spigot in an effectual manner, the spigot being readily removable for cleaning and other purposes. Still another object is to provide for rapid and efficient cooling of the molds by constructing the bottom of the molds in a manner peculiarly adapted for quick cooling and by continuously applying cold

water to the bottoms of the molds by means of a water supplying and circulating system of novel design.

These and other objects and attendant advantages will be more readily appreciated as the invention becomes better understood by reference to the following description when considered in connection with the accompanying drawings, in which—

Fig. 1 is a plan view of a furnace embodying my improvements;

Fig. 2, a side elevation of the furnace;

Fig. 3, a vertical sectional view therethrough with the legs removed and only a portion of the hood shown;

Fig. 4, a fragmentary sectional view taken on the line 4—4 of Fig. 3;

Fig. 5, a fragmentary view, partially in section, showing the drain for maintaining a water level in the mold cooling reservoir;

Fig. 6, a sectional view taken substantially on the line 6—6 of Fig. 3, with the valve actuating member removed;

Fig. 7, a plan view of the furnace, partially in section; and

Fig. 8, a horizontal sectional view taken substantially on the line 8—8 of Fig. 3 with the molds removed.

While my improvements are especially adapted to be used in printing establishments for the purpose of melting and remelting linotype metal and type slugs and casting pigs for the melting pot of a linotype machine, it should be understood that the invention contemplates the melting and pouring of soft metals for various purposes well understood in the use of such metals. Consequently, the drawings and following description illustrate only one practical embodiment of my invention.

In the present instance, a suitable body and supporting structure for the melting pot is provided, in the form of a cylindrical body 9 which may be of boiler plate metal, supported by legs 11. The open-top melting pot 12 formed with a flanged top rim 13 which rests on the top of the body 9 so as to suspend the melting pot within the body, is of less diameter than said body so that a confined heating space 14 is established circumferentially about the pot throughout the entire length thereof. Thus, the heat products arising from a suitable burner, designated generally by character 15, positioned

below the pot will not be dissipated or passed away, but will be confined and utilized to the fullest extent in heating the pot. Suitable means, such as small angle plates 5 16, may be employed to position the pot centrally within the body 9. This body may be heat insulated by the provision on its interior of an asbestos lining 17.

In order that the gases arising from the 10 products of combustion may be effectually carried away and the melting pot may be inclosed during the melting process, I have provided a hood covering the top of the pot and constructed to allow access thereto, 15 and also to receive the rising gases from the heating space 14. The hood may be of sectional construction, comprising a stationary back 18 circumscribing the body 9 only at the back thereof and attached in spaced relation thereto by suitable bolts 19, and a front movable section 21 hinged to the back section and shaped to allow an opening 22 at the front of the furnace for a valve operating member described hereinafter. The 20 rising gases pass upwardly in the space 14 through a plurality of openings 23 in the rear wall only of the body 9 adjacent to its top, as shown in Fig. 7, and pass upwardly into the hood and thence through an outlet 30 in its top and away through a suitable flue.

The heating means may be of suitable design, although I find that a gas burner serves the purpose very efficiently and I have therefore, as mentioned above, provided a gas burner 15, supplied with gas through the piping 24 and adapted to be lighted by the pilot light 25 which blows a flame through an opening in the body 9. The burner, its air mixing valve and lighter, 40 may, of course, be of any suitable construction; and in the present instance, I have omitted the gas openings from one sector of the burner, as shown in Fig. 8, so that the spigot through which the metal is poured 45 may be positioned directly above the sector without being subject to injury by the heat, although as mentioned hereinafter, the spigot may be easily removed from the furnace during the period that the metal is being heated; if desired. It will be manifest that metal placed in the pot through the 50 opening afforded by the removable hood section will be melted by the application of heat from the burner.

55 The means for drawing off or pouring the metal will now be described, reference being had especially to Fig. 3. The metal is drawn off through a valve-controlled outlet in the bottom of the pot and delivered 60 through a spigot for pouring. A simple tapered cylindrical valve 26 fits revolvably in a casing 27 and is adapted, when oscillated, to open and close the outlet from the pot by movement of its port 28 into and out of registration with the opening 29 in the casing.

The valve casing has a reduced threaded end 31 extending through the bottom of the pot, and a nut threaded on this end secures the casing in position, a gasket being interposed between the casing and the pot at the 70 inside thereof. This valve may be manually operated from the front of the furnace by means of a hand lever 33 projecting through the opening 22 and secured at its inner end to a rock shaft 34 co-axial with the valve 26, 75 rotatable at its upper end in a cross bar 35 secured to and spanning the top of the melting pot, and shaped at its lower end to provide a square socket adapted to receive the square end of the valve. It will be manifest that by swinging the hand lever 33 laterally, the valve will be closed and opened, controlling the flow of metal from the melting pot, and if desired, the valve actuating means may be removed by simply withdraw- 80 ing the rock shaft axially.

Upon the lower end 31 of the valve casing is threadedly mounted so as to be freely rotatable thereon, a spigot-carrying member designated generally by reference character 90 37. This, as shown, is shaped to receive and position the receiving end of a spigot 38 directly below the outlet of the pot so that the metal will flow directly into the spigot. The spigot, it will be noted, is an elongated 95 channel shaped member extending through an opening 39 in the body 9 and having a spout 41 through which the metal is delivered. The spigot, resting intermediate its ends at the point 42 on the member 37 100 and engaging behind the edge 43 thereof, is supported in an inclined manner as shown, so that the metal will flow freely to the spout. By reason of this construction the spigot is freely detachable from its supporting member. To remove the spigot, its outer end may be raised so as to withdraw its inner end from the edge 43, whereupon the spigot may be freely withdrawn lengthwise from its supporting member and 110 through the opening 39. The supporting member 37, it will be seen, pivotally supports the spigot so that the delivery end thereof, manipulated by means of the handle 44, may be swung laterally to successively 115 pour a number of laterally spaced molds set in front of the furnace. The operation may be performed very easily and quickly, since the operator guides the spigot with one hand and with the other moves the valve lever 33, 120 so that the metal may be started and stopped at will.

Coming now to the molds into which the metal is poured, it will be seen by reference to Figs. 4 and 7, that I have in the present 125 instance illustrated a means for supporting three molds, each constructed to cast three pigs suitable for use in the small melting pots of linotype machines. It should be understood, however, that the invention is 130

in no way limited to this number of molds or to the particular number of pigs to be cast by each mold, since these might be varied according to special requirements.

5 However, the arrangement illustrated has been found particularly satisfactory and efficient and is especially rendered so and made possible in view of the employment of a novel cooling means, which will be presently described. An open-top reservoir 45 mounted on the front of the furnace body just below the opening 39, as shown, is constructed to support a plurality, three in the present instance, of removable molds, designated generally by 46. Each mold comprises a marginal portion 47 adapted to rest on the top supporting surface of the reservoir, a handle extension 48 by means of which the mold may be lifted into and out of position and conveniently handled, and the mold body proper which depends below the marginal portions 47 and is shaped to provide two longitudinal partitions 49 designed to equally divide the mold into three 25 open-top mold compartments for the casting of three pigs or blocks. Instead of making the bottoms of the molds flat, or substantially so, as is the ordinary practice, I have shaped the bottoms to obtain as large an exposed surface as possible. This is done by forming the partition walls 49 in inverted V-shape in cross-section, forming each mold compartment with a central longitudinal raised ridge 51, and forming the bottom of the mold to conform substantially to the shape of the inside of the mold, as shown plainly in Fig. 4. Thus, when the bottom of the mold is immersed in cold water contained in the reservoir a large under-surface 30 will be exposed to the water, so that when the metal is poured it will be quite rapidly and uniformly cooled by the effect of the cold water on this large area. It will be especially noted that the cooling effect is felt on the sides and ends of each block and centrally along its core, by reason of the ridged center 51. A greater cooling effect is obtained by initially discharging the cold water directly against the underside of the 40 molds from jets or nozzles positioned directly beneath and in close proximity to the molds. A suitable means for this purpose consists of a series of nozzles 52, one being positioned beneath each mold in the manner shown so that the water discharging from each nozzle strikes that portion of each mold compartment which is heated most quickly. These nozzles having a plurality of discharge outlets may be of any suitable 45 construction, and in the present instance, are formed of ordinary pipe fittings. Each nozzle receives its supply from a central pipe 53 passing through the bottom of the reservoir and joined to a main water supply pipe 54, as shown. The water is main-

tained at a given level, such for example as illustrated in Figs. 4 and 5, by an overflow drain 55, the function of which is obvious.

In the use of my improvements, the metal in the pot is heated to the desired temperature by the gas burner, the spigot being either removed or moved to its extreme left hand limit during the melting process so as not to become unduly heated. A continuous circulation of water is maintained, so that the molds will be maintained in a cooled condition and no time need be lost in waiting for molds to cool. The operator, by manipulation of the spigot and valve lever 33, may successively pour the molds as described above. Since the metal cools very quickly under the influence of the special cooling means, it will be manifest that an operator may in quick succession recast the molds until the supply of metal is exhausted without any danger of the molds becoming heated to such an extent as to cause splashing and spattering of the water, such as occurs in the use of metal furnaces of other constructions. Consequently, the advantages following from the continuous circulation of water, the special arrangement and manner in which the cold water is supplied, and the special construction of the molds are extremely desirable and effectively serve to promote not only efficiency in operation but uniformity in the shape and size of the resultant pigs.

I claim:

1. A melting furnace of the character described, comprising a melting pot, a member passing through the bottom thereof rigidly secured thereto and having a valve controlled passage through which metal may be delivered from the pot, a spigot-carrying member pivotally mounted on the first named member, and a spigot detachably mounted on said pivoted member and adapted to receive metal from said passage and to be swung laterally at its free end to deliver the metal at laterally spaced points.

2. In a melting furnace of the character described, a melting pot, a member extending through the bottom wall of the melting pot and having a port through which molten metal is adapted to be delivered from the pot, a valve for closing and opening said port and operable from the exterior of the pot, a spigot, and a member pivotally mounted on said extended end of the port-containing member and shaped to detachably receive and support the spigot.

3. In a melting furnace, a melting pot, a valve-carrying member passing through the bottom of the melting pot and having a tapered port therethrough, a tapered valve seated in said port, means for operating the valve from the exterior of the pot, a spigot-carrying member rotatably mounted on said

100.

105.

110.

115.

120.

125.

130.

valve-carrying member to turn about a vertical axis, and a spigot detachably mounted on said spigot-carrying member.

4. In a melting furnace of the character described, a melting pot having a delivery outlet, a spigot-carrying member mounted to turn about a vertical axis, and a spigot resting intermediate its ends upon said member and having an upper part engaged behind a part of said member in such manner as to hold the spigot in operative position but permitting removal thereof by raising the delivery end of the spigot to disengage said spigot part from said member.

5. In a melting furnace of the character described, a melting pot having a bottom delivery outlet, a member supported from the melting pot beneath said outlet and rotatable about a vertically disposed axis, a spigot having a receiving end and a delivery end, and means effecting an interlocking engagement between the receiving end of the spigot and said member, whereby the spigot is supported in operative position on said member and is detachable therefrom by movement of the spigot relatively to said member out of said interlocking engagement.

6. In a melting furnace of the character described, a melting pot having a bottom

opening, a member below said opening mounted to turn about a vertical axis, and a spigot on said member having an inner end arranged to receive metal through said opening in the pot and an outer delivery end, the spigot being so mounted on said member as to be pivotal upon and with respect thereto about an axis intermediate the ends of the spigot, such pivotal movement bringing the spigot into and out of operative position on said member and when in inoperative position permitting free detachment of the spigot from said member.

7. In a melting furnace of the character described, a melting pot having a delivery outlet, a member pivotally mounted to turn about a vertical axis and having a spigot-receiving socket, and a spigot having an end shaped for insertion into said socket whereby the spigot is supported by said member in position to receive metal through said outlet from the melting pot, and means operative between said member and the spigot for holding said parts in coöperative relation and permitting quick detachment and removal of the spigot from the member only by a disengaging movement of the spigot away from its operative position.

GARNET W. McKEE.
